UNITED STATES PATENT OFFICE

JONAS TOROLF, OF TAFT, CALIFORNIA.

MOUNTING FOR SLIDING DOORS.

1,191,370.

Specification of Letters Patent. Patented July 18, 1916.

Application filed June 1, 1914. Serial No. 842,267.

To all whom it may concern:

Be it known that I, JONAS TOROLF, a subject of the King of Sweden, residing at Taft, in the county of Kern, State of California, have invented certain new and useful Improvements in Mountings for Sliding Doors; and I do hereby declare the following to be a full, clear, and exact description of the invention, such as will enable others skilled in the art to which it appertains to make and use the same.

This invention relates to mountings for sliding doors.

The object of the invention resides in the provision of an improved mounting for sliding doors whereby the door will partake of true horizontal movement in opening and closing and binding of the door during such opening and closing movement positively eliminated.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a view in elevation showing the improved mounting associated with a sliding door, the latter being in open position; Fig. 2, a fragment of what is shown in Fig. 1 with the door in closed position; Fig. 3, a section on the line 3—3 of Fig. 2; and Fig. 4, a perspective view of the connection between the door and studding.

Referring to the drawings A indicates a sliding door frame including a vertical studding 10, while B indicates a sliding door mounted in the frame A. Secured to the side of the studding 10 adjacent the door B is a plate 11 to which is pivotally connected upper and lower arms 12 and 13 respectively, said arms being of equal length. Secured to the edge of the door B adjacent the studding 10 is a plate 14 to which is pivotally connected upper and lower arms 15 and 16 respectively of a length equal to the arms 12 and 13, the pivot of the arm 15 being in the same horizontal plane with the pivot of the arm 12, while the pivot of the arm 16 is disposed in the same horizontal plane with the pivot

of the arm 13. The free ends of the arms 12 and 15 are pivotally mounted between the arms of a bifurcated member 17 and fixed to the free ends of the arms 12 and 15 are meshing segmental gears 18 and 19 respectively. The free ends of the arms 13 and 16 are pivotally mounted between the arms of a bifurcated member 20 and fixed to the free end of the arms 13 and 16 are meshing segmental gears 21 and 22 respectively. The bifurcated members 17 and 20 are connected by a rod C formed of sections 23 and 24 connected by a turn buckle 25 whereby said rod may be lengthened and shortened.

From the foregoing construction it will be apparent that as the arms 12 and 13 move down an equal movement will be imparted to the arms 15 and 16 by reason of the meshing gears 18 and 19 and the meshing gears 21 and 22 which will result in true horizontal movement of the door B toward the studding 10. By reason of the connection between the door and studding it will be obvious that the possibility of the door sagging and binding is entirely obviated. In the case of relatively light doors one pair of gears can be dispensed with but in the case of heavy doors connections between the door and studding of substantially the type illustrated and described will be necessary to effect equal distribution of the strain throughout different parts of the connections.

What is claimed is—

1. The combination with a vertical studding and a horizontally sliding door, of one pair of upper and one pair of lower arms pivotally connected to the studding and door respectively, uniting elements connecting the free ends of the upper and lower arms respectively, meshing gears fixed to the free ends of one pair of arms, and a connecting rod between the upper and lower uniting elements.

2. The combination with a vertical studding and a horizontally sliding door, of one pair of upper and one pair of lower arms pivotally connected to the studding and door, uniting elements connecting the free ends of the upper and lower arms respectively, gears fixed to the free ends of the upper and lower pairs of arms, the gears meshing on each pair, and a connecting rod between the upper and lower uniting elements.

3. The combination with a vertical stud-

ding and a horizontally sliding door, of one pair of upper and one pair of lower arms pivotally connected to the studding and door, uniting elements connecting the free ends of the upper and lower arms respectively, meshing gears fixed to the free ends of the lower pair of arms, and a connecting rod between the upper and lower uniting elements.

10 4. The combination with a vertical studding and a horizontally sliding door, of one pair of upper and one pair of lower arms pivotally connected to the studding and door, uniting elements connecting the free

ends of the upper and lower arms respectively, gears fixed to the free ends of the upper and lower pairs of arms, the gears meshing on each pair, a connecting rod between the upper and lower uniting elements, and means for lengthening and shortening 15 20 said connecting rod.

In testimony whereof, I affix my signature, in the presence of two witnesses.

JONAS TOROLF.
